UNITED STATES PATENT OFFICE.

JAMES M. LINDSEY, OF MONTGOMERY, ALABAMA.

DESIGN FOR A BOTTLE.

Application filed September 16, 1926. Serial No. 19,088. Term of patent 14 years.

To all whom it may concern:

Be it known that I, JAMES M. LINDSEY, a citizen of the United States, residing at Montgomery, city of Montgomery, in the county of Montgomery and State of Alabama, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

JAS. M. LINDSEY.
